SHEET FEEDING APPARATUS

Frederick G. Binder, Philadelphia, Pa., assignor to
 Dexter Folder Company, Pearl River, N. Y., a
 corporation of New York

Application July 12, 1940, Serial No. 345,041

5 Claims. (Cl. 271—27)

This invention relates to sheet feeders and more particularly to sheet handling devices thereof comprised by suction sheet separators and forwarders.

At the present time various types of sheet feeders employ sheet handling means comprised by vacuum operated telescoping suction devices for separating and/or forwarding sheets of paper, cardboard or the like from a supply thereof. These suction devices each include a cylinder having a piston slidably mounted therein and provided with a hollow piston stem to which is attached, exteriorly of the cylinder, a sheet engaging rubber suction cup. Vacuum is created in each cylinder and beneath the piston through a port formed in said cylinder to draw the piston, the piston stem and suction cup downwardly until the latter engages the uppermost sheet of the supply. Upon closing of the suction cup by the sheet, vacuum is then created above the piston and in the piston stem and suction cup through another port to lift the piston, the piston stem, the suction cup and the sheet engaged thereby.

Upon continued operation of the suction devices, particularly on printed stock which has been previously coated with paraffin, the ports, through which vacuum is created to lift the pistons, the piston stems and the suction cups, become clogged with paper dust, particles of paraffin or other foreign substances resulting in faulty operation of said suction devices. When this occurs it becomes necessary to stop the feeder, remove the clogged suction device or devices therefrom and dismantle the same to clean out the paraffin, paper dust or other foreign substance. This is objectionable for the reason that it decreases the running time of the feeder with resulting decrease in production thereof and loss of profit to the printer.

Accordingly, it is one object of the present invention to provide improved vacuum operated suction devices of the telescoping type for acting on sheets of paper, cardboard or the like, and which overcome the above mentioned objection.

Another object of the present invention is to provide a sheet feeder having improved vacuum operated suction devices of the telescoping type the ports of which may be cleaned without stopping the feeder and without dismantling or removing said devices therefrom.

Another object of the present invention is to provide improved vacuum operated suction devices of the telescoping type the ports of which may be cleaned through the provision of novel means incorporated therein for this purpose.

These and other objects of the present invention will appear as the following description thereof proceeds and in order to more clearly understand said invention reference may be had to the accompanying drawing which illustrates one embodiment thereof.

In said drawing:

Fig. 1 is a fragmentary vertical longitudinal sectional view of a sheet feeder embodying the present invention; and

Fig. 2 is an enlarged vertical longitudinal sectional view of one of the vacuum operated telescoping suction sheet handling devices illustrated in Fig. 1.

15 Referring to the drawing, wherein like reference characters designate like parts throughout the several views, 5 indicates a frame comprised at opposite sides of the feeder by front uprights 6 and rear uprights 7 connected together by side members 8. A pile board 9 and pile of paper or cardboard sheets 10 is supported in the feeder on a pile elevator (not shown) which is of well known construction and operation and needs no detail description herein except to say that as 20 sheets are fed off the top of the pile, the elevator and pile board 9 are intermittently raised in the usual manner to keep the top of said pile at a proper level for separation and feeding of sheets therefrom.

30 The sheets of pile 10 are separated one after another from the top and rear thereof by separating devices located adjacent the rear corners of the pile and actuated in opposite directions by vacuum to engage and lift the rear portion of the topmost sheet. The separating devices, indicated broadly at 11, are carried by brackets 12 which are mounted on, and slidable along, a rear cross member 13. This cross member 13 forms part of an auxiliary frame 14

40 which includes side members 15. The auxiliary frame 14 is pivotally mounted at opposite sides of the feeder, as at 16, on brackets 17 which are bolted or otherwise suitably secured to the side members 8. The auxiliary frame 14 is supported 45 at the rear thereof by pins 18 secured in any suitable manner in the rear uprights 7.

Each sheet separated by the separating devices 11 is advanced from the pile by forwarding devices located adjacent the front of said pile and actuated in opposite directions by vacuum to engage and lift the front portion of the separated sheet. The forwarding devices, indicated broadly at 19, have swinging movement to advance the separated sheets, and for this purpose said devices are secured to arms 20 fixed on a rock shaft

21 which extends transversely of the feeder and is journalled in suitable bearings in the brackets 17. The sheet forwarding devices 19 are rocked rearwardly by a spring (not shown) and forwardly by a cam 22 fixed on a cam shaft 23 which extends transversely of the feeder and is journalled in suitable bearings in the front uprights 6. The cam shaft 23 is driven in any suitable manner from any suitable source of power, as for example, the printing press or other machine with which the feeder is associated. The cam 22 engages a roller 24 journalled on a cam strap 25 extending over the cam shaft 23 and connected with an arm 26 which is fixed on the rock shaft 21.

30 The sheets separated from the pile by the sheet separating devices 11 are taken by the sheet forwarding devices 19 and delivered thereby to a conveyor comprised by a driven feed roller 27 which extends transversely of the feeder and is journalled in suitable bearings in the front uprights 6. Cooperating with the feed roller 27 are drop rollers 28 journalled on arms 29 which are fixed on a rock shaft 30. The rock shaft 30 extends transversely of the feeder and is journalled at opposite ends thereof in suitable bearings in plates 31 which are bolted or otherwise suitably secured to the front uprights 6. The drop rollers 28 are raised and lowered in the usual manner once during each cycle of operation of the feeder to receive the forwarded sheets delivered between said roller and the feed roller 27 and thereafter assist feeding of the sheets by the feed roller toward the machine or instrumentality to be fed.

35 The suction sheet separating devices 11 and the suction sheet forwarding devices 19 are identical as respects their construction and sheet engaging and lifting operation and a description of one of said devices will therefore be sufficient for all of the same. These suction devices are, in accordance with the present invention, each preferably constructed and operated as follows. Referring now more particularly to Fig. 2, each suction device is comprised by a cylinder 32 closed at its upper and lower ends by caps 33, 34, respectively, secured in any suitable manner in said cylinder. Slidably mounted in the lower cap 34 of the cylinder 32 is a hollow piston stem 35 which is open at both ends and projects through said cap downwardly beyond the same. Fixed on the lower projecting end of the hollow piston stem 35 exteriorly of the cylinder 32 is a rubber suction cup 36 provided with a duct 37 in communication with said cup and said tube through the lower open end of the latter.

40 Slidably mounted in the cylinder 32 and secured to or formed integrally with hollow piston stem 35 at the upper end thereof is a piston head 38 provided with a skirt 39. Surrounding the hollow piston stem 35 and interposed between the head 38 and the lower cap 34 of the cylinder 32 is a light spring 40 adapted to normally hold said head, said piston stem and the suction cup 36 in their normal full line positions shown in Figs. 1 and 2.

45 Bolted or otherwise suitably secured to the lower end of the cylinder 32 exteriorly thereof is a bracket 41 having formed therein a chamber 42. This chamber 42 communicates with the interior of the cylinder 32 through a port 43 formed in said cylinder and through a recess 44 formed in the lower cap 34. Connected with the bracket 41 and communicating with the chamber 42 therein is one end of a vertically extending con-

5 duct 45 the opposite end of which is connected with one end of a short conduit 46 through the medium of a flexible coupling 47. The opposite end of this short conduit 46 is connected with one end of a conduit 48 which is formed in, and extends vertically through, a horizontally disposed block 49. Connected with the opposite end of the conduit 48 in block 49 is one end of a flexible conduit 50 the opposite end of which is connected with a vacuum pump (not shown) or other suitable source of vacuum through a suitable valve mechanism (not shown) which controls the making and breaking of vacuum in the cylinder 32 at predetermined intervals.

55 15 Formed in the block 49 and communicating with the conduit 48 therein is a port 51 which is somewhat smaller than the port 43 in the lower end of the cylinder 32. This port 51 in block 49 opens into a chamber 52 which is also formed in said block. The chamber 52 is closed by a plug 53 having threaded engagement with the block 49. Connected with the cap 33 of cylinder 32 and communicating with the interior of said cylinder is one end of a vertically extending conduit 54 the opposite end of which is connected with one end of a short conduit 55 through the medium of a flexible coupling 56. The opposite end of this short conduit 55 is secured in the block 49 and connected with the chamber 52 in said block.

60 20 Slidably mounted in the plug 53 and disposed in line with the port 51 is a port cleaning member comprised by a pin 57 having an enlarged portion 58 disposed within the chamber 52 and a reduced portion 59 also disposed within said chamber and adapted to enter the port 51. The enlarged portion 58 of pin 57 prevents outward displacement of said pin from the plug 53 and is smaller in diameter than the chamber 52 so that when vacuum is created in said chamber, as hereinafter described, said vacuum will have no effect on the pin. Surrounding the pin 57 and interposed between the plug 53 and a head 60 formed on the outer end of said pin, is a spring 61 which normally holds the pin in the full line position thereof shown in Fig. 2 so that the reduced or port cleaning portion 59 of said pin is removed from the port 51.

65 25 The operation of the suction device which has just been described is substantially as follows. When vacuum is created in the flexible conduit 50 vacuum will likewise be created in the cylinder 32 and beneath the piston head 38, through the conduits 48, 46, 45, the chamber 42, the port 43 and the recess 44. Vacuum so created in the cylinder 32 acts on the underside of the piston head 38 and draws said head, the piston stem 35 and the suction cup 36 downwardly against the action of the spring 40 until the suction cup engages the top sheet of the pile 10. Immediately upon closing of the suction cup 36 by the top sheet of the pile, vacuum will be created in the cylinder 32 above the piston head 38 and in the piston stem 35 and suction cup 36, through the port 51, the chamber 52 and the conduits 55, 54. Vacuum so created in the cylinder 32 acts on the top side of the piston head 38 and over an area which is greater than the area on the underside of said piston head, thus lifting the piston head 38, the piston stem 35, the suction cup 36 and the top sheet engaged by vacuum therewith.

70 30 Upon continuous operation of the suction device, particularly on printed sheets which have been previously coated with paraffin, particles of paraffin, paper dust or other foreign substances

are drawn by vacuum through the suction cup 36 which eventually clog up the port 51 in block 49 resulting in sluggish operation of the suction device or failure of said device to operate. When this occurs, the machine attendant simply presses the pin 57 inwardly and through the port 51 while the feeder is in operation, thereby forcing the port clogging substance from the port 51 into the conduit 48 from which it is discharged by vacuum through the flexible conduit 50. When the pin 57 is released by the machine attendant, said pin is returned to its normal full line position, shown in Fig. 2, through the expanding action of the spring 61.

The present description and accompanying drawing set forth with more or less particularity one embodiment of the present invention, but it is to be expressly understood that said invention is not limited to said embodiment or otherwise than by the terms of the appended claims.

What I claim is:

1. In a cylinder and piston type vacuum operated sheet handling device having a port for establishing communication between a source of vacuum and the interior of the cylinder, the combination of means incorporated in the device movable at any time through the port thereof to clean it, and means normally holding said first named means removed from the port to enable operation of said device.
2. In a cylinder and piston type vacuum operated sheet handling device having a port for establishing communication between a source of vacuum and the interior of the cylinder, the combination of a chamber interposed between and in communication with the cylinder and the port and disposed in line with the latter, a member incorporated in the device movable at any time through said chamber and said port to clean the latter, and a spring normally holding said member removed from the port to enable operation of said device.
3. In a cylinder and piston type vacuum operated sheet handling device having a conduit

5 connected with a source of vacuum and a port for establishing communication between the conduit and the interior of the cylinder, the combination of means incorporated in the device movable at any time through the port and toward the conduit to dislodge foreign matter from said port into said conduit, and means normally holding said first named means removed from the port to enable operation of said device.

10 4. In a cylinder and piston type vacuum operated sheet handling device, the combination of a pair of conduits having corresponding ends connected with the cylinder at the top and bottom thereof respectively, a block connecting the opposite ends of said conduits together, a conduit in said block and connecting one of said first named conduits with a source of vacuum, a port in the block and communicating with the conduit therein, a chamber in the block and connecting the port therein with the other of said first named conduits, and a member continuously extending into the chamber and movable at any time through the port for dislodging foreign matter from said port to clean the same, said member being normally removed from the port to enable operation of said device.

15 5. In a cylinder and piston type vacuum operated sheet handling device, the combination of a pair of conduits having corresponding ends connected with the cylinder at the top and bottom thereof respectively, a block connecting the opposite ends of said conduits, a conduit in said block and connecting one of said first named conduits with a source of vacuum, a port in the block and communicating with the conduit therein, a chamber in the block and connecting the port therein with the other of said first named conduits, a member extending into the chamber and movable through the port for dislodging foreign 20 matter from said port to clean the same, and a spring normally holding said member removed from the port.

FREDERICK G. BINDER.
